UNITED STATES PATENT OFFICE.

ELIZABETH MISTELSKI AND THEODOR MISTELSKI, OF ALLIANCE, OHIO.

SAND-MOLDING MACHINE.

No. 800,758.

Specification of Letters Patent.

Patented Oct. 3, 1905.

Application filed August 3, 1904. Serial No. 219,297.

To all whom it may concern:

Be it known that we, ELIZABETH MISTELSKI and THEODOR MISTELSKI, citizens of the United States, residing at Alliance, in the county of Stark and State of Ohio, have invented new and useful Improvements in Sand-Molding Machines, of which the following is a specification.

Our invention relates to sand-molding machines.

The object of the present invention is to provide improvements on the sand-molding machines set forth in the patents to Theo. Mistelski, No. 430,666, dated June 24, 1890, and No. 450,521, dated April 14, 1891, particularly in the provision of novel tamping mechanism whereby a plurality of tampers are employed, each being yieldably independent of the others and moving all of the tampers as a unit or bank to supply pressure to the sand or moving the carriage and mold toward the tampers for the same purpose, and providing improved means for raising and lowering the pattern on the carriage without any binding effects, and, further, to make provision for novel means for jarring or vibrating the pattern in a general backward-and-forward direction to cause the sand to settle about the pattern and insure the best possible tamping effect by the tampers and to jar or vibrate the pattern in a general up-and-down direction to clear it from the mold and permit its easy withdrawal without the use of stripping-plates or other clearing devices.

The invention also contemplates the provision of other improved features, which, together with the detailed construction of the machine, will be fully described hereinafter and the novel features recited in the appended claims.

In the accompanying drawings, Figure 1 is a side elevation; Fig. 2, a vertical section on line *xx* of Fig. 1; Fig. 3, a longitudinal detail section of the carriage; Fig. 4, a cross-section on line *44* of Fig. 3; and Figs. 5 and 6, views showing different ways in which steam, air, or hydraulic pressure may be applied.

The frame consists of a bed 1 and uprights 2 or standards. The bed 1 has rails 3, on which the wheels 4 of carriage 5 run, and stops 6 may be employed to position the carriage at the proper point, it being understood that, if desired, another carriage may be employed with flask and banking-frame to be run under the frame 2 after the first carriage

is removed to form the second half of the mold. Only one carriage can be used, if desired. The carriage is provided with a vertically-sliding rectangular frame 7, on which the pattern 8 is supported and adapted to be positioned by said frame inside of the flask 9, which has the banking-frame 10 superposed thereon. To raise and lower the frame 7, we provide eccentrics 11, secured on a longitudinally-extending shaft 12, equipped with an operating-crank 13, said eccentrics working in straps or blocks 14 on the frame 7, the eccentrics being located at the ends of said frame. By the use of two eccentrics thus positioned there is no binding as the frame 7 is raised and lowered and it is secured where positioned.

The top of frame 7 consists of a longitudinally-movable pattern-table 15, to which the pattern 8 is secured by a bolt 16, extending loosely through said table 15, and a spring 17, operating on said bolt, holds the pattern yieldingly down on the table. The table 15 is supported on rollers 18, carried by frame 7, and it has depending lugs 19. Carried by frame 7 is a cylinder 20, in which is a movable piston 21, carrying at its opposite ends knockers or rappers 22, adapted to strike against the lugs 19 in alternation as the piston is rapidly vibrated by the pressure—such as air, steam, or other fluid supplied to the cylinder 20 by a flexible hose 23—thus shaking the table 15 to and fro horizontally a limited distance and with it the pattern. Suitable automatic valve 24 is employed, by preference, to admit and exhaust the air from the cylinder 20, and in addition a controlling-valve 25 may be employed to completely cut off the pressure. The object of this mechanism is to vibrate the pattern in the sand as the tamping mechanism is acting to cause the sand to settle around the pattern and be better compacted or compressed by the tampers, which otherwise might not be able to pack the sand with equal density. Another cylinder 26 is carried by frame 7, and within said cylinder is a vibratory piston 27, having a rapper 28, adapted to strike on the bolt 16 and vibrate the pattern up and down, suitable automatic valve mechanism 28' being employed to admit and cut off pressure to the said piston, and a controlling-valve 29 is also used in the flexible hose 30, which supplies pressure to cylinder 26 for the purpose of stopping the action of the piston 27. The purpose of this mechanism is to vibrate the pattern up and

down in the mold after the mold has been tamped and after the pressure vibrating mechanism for shaking the table 15 has been stopped, and the effect is to completely free or clear the pattern from the mold and leave the mold sharp, clean, and unbroken, so that the pattern can be removed from the mold by lowering the frame 7 after the mold has been completed without danger of injuring the imprint and obviating the use of a stripping-plate.

On the standards 2 are stationary pistons 31, above and below which open out ports 32 and 33, or separate pipes could be used, if desired. The ports 32 are connected by a pipe 34 and the ports 33 by a pipe 35, pressure to pipes 34 and 35 being controlled by a four-way valve 36. A suitable pressure-gage 37 may also be used. The tamping box or frame 38 slides up and down on the standards 2 and is provided with the cylinders 39, having suitable stuffing-boxes at their ends, said cylinders sliding on the pistons 31. The tamping-frame 38 has cross-pieces 40 and 41, through which slide the independently-mounted tampers 42, having feet 43, adapted to operate in the flask at various points to completely tamp or pack all of the sand. Any number of rows of these tampers arranged in any manner can be employed. On the upper ends of the tamper-rods are nuts 44, by the adjustment of which the amount of play of the tampers is regulated. Each tamper-rod also carries a collar 45, between which and the upper cross-piece 40 of the tamping-frame is a coil-spring 46, one spring being provided for each tamper-rod. It will therefore be seen that the tampers are all carried by the tamping-frame and move as an entirety with said frame, but that each tamper is independently spring-pressed and its play can be regulated independently of the other tampers and that each tamper will accommodate itself to the sand irrespective of the action of the other tampers.

When a pattern has low and high parts, so that the sand above them is deep in some places and shallow in others, it will not do to tamp all parts with the same pressure, because that would pack the sand harder where it is shallow. In order to effect a uniform pressure, the tampers above the high parts of the pattern are adjusted to a higher level than the others by means of the nuts 44. The lower tampers then operate first on the deep sand, and after that has been well rammed the other tampers act on the shallower portions. This produces a more even and uniform pressure than if all the tampers had been brought down upon the sand at once. It also avoids the danger of injuring the high parts of the pattern.

Operating the valve 36 one way admits pressure to pipe 34 and causes the pressure admitted to the cylinders 39 to force the tamp-

ing-frame and tampers down to act upon the sand, and operating the valve 36 another way cuts off and exhausts the pressure below the pistons 31 and admits pressure above said pistons 31, thereby raising the entire tamping-frame. These operations can be carried on as many times as may be desired to properly tamp or compact the sand around the pattern, after which the tamping-frame is raised and the carriage wheeled away, the frame 7 lowered to withdraw the pattern, and the flask removed for purposes of casting; but prior to withdrawing the pattern the same will be vibrated up and down to clear it of the mold by the use of the pressure vibrating mechanism herein set forth. During the tamping operation before described the pattern and table 15 are vibrated horizontally by the pressure vibrating mechanism to insure a settling of the sand and proper tamping thereof.

Fig. 5 illustrates the manner in which a single cylinder 47 can be used to raise and lower the tamping-frame 38. The tamping-frame 38 has guides 48, which slide on the uprights 2, and is connected to a piston-rod 49, having piston 50, operating in cylinder 47. The pressure is admitted at opposite ends of the cylinder at different times by manipulating a valve 51.

In Fig. 6 the tamping-frame 38 is secured to the uprights 2, and the carriage is raised and lowered relatively to the tampers by employing a cylinder 52, piston 53 operating therein and sustaining the track-platform 54 of the carriage, which latter is guided on the uprights 2. Pressure to the cylinder 52 is controlled by a valve 55.

The flask having been placed on the carriage and the latter properly positioned beneath the tampers, the crank 13 is operated to raise the pattern-table 15 to constitute the bottom of the flask, the pattern having been secured on the table. The sand is then introduced into the flask and air or fluid pressure applied to relatively advance the tampers and the carriage, more sand being introduced and the tamping-frame and carriage being relatively retreated and advanced as the operation proceeds. The different tampers yield independently and accommodate themselves to the sand and to the pattern, and their play can be limited as found desirable. While the tamping operation is proceeding the operator turns pressure into cylinder 20 to cause a forward-and-backward vibration of the table 15 in order that the sand may properly settle as it is tamped, and thus conform to the pattern. After the mold has been formed pressure is let into the cylinder 26 to vibrate the pattern up and down to cause it to clear itself from the mold, and the carriage and tamping-frame are relatively moved to separate them, the vibrating mechanisms having been stopped. The carriage is then wheeled away and the pattern lowered out of the mold.

by operating the crank 13. The flask can then be removed. A separate carriage can be used to form the other half of the mold while the first carriage is being moved away

5 or the same carriage can be used again.

It will be understood that our invention contemplates the relative movement of the carriage and tamping devices, and either the carriage or the tamping device may be moved.

10 Various changes of construction may be resorted to in carrying out the invention, and other embodiments thereof than those shown and described may be used.

Having thus described our invention, what 15 we claim as new, and desire to secure by Letters Patent, is—

1. In a sand-molding machine, the combination with a flask, of a tamping-frame having a series of upper and lower guides, a series of 20 independently-movable tampers having stems slidable in the upper and lower guides, collars on the tamper-stems, coil-springs on the said stems interposed between the collars and the upper guides, adjustable nuts on the upper 25 ends of the stems which limit the play of the tampers, and constitute means for independently tensioning the springs, whereby the play and tensioning of the tampers may be independently regulated, and means for moving the tamping-frame and flask relatively to each other.

2. In a sand-molding machine, the combination with a flask, of a movable pattern-support, means for vibrating said support horizontally, and separate means for vibrating it 35 vertically.

3. In a sand-molding machine, the combination with a flask, of a pattern-support, a pattern, an anvil extending loosely through the 40 pattern-support, a spring coöperating with

the pattern to hold it down on the pattern-support, and a hammer for striking said anvil to vibrate the pattern up and down in the flask.

4. In a sand-molding machine, the combination with a flask, of a pattern-support, a pattern, an anvil extending loosely through the pattern-support, a spring coöperating with the pattern to hold it down on the pattern-support, an independent pressure-cylinder, a 45 pressure-operated piston in the cylinder, and a hammer operated by said piston adapted for striking said anvil to vibrate the pattern up and down in the flask.

5. In a sand-molding machine, the combination with a flask, of a horizontally-vibratable pattern-support for the flask, an independent pressure-actuated hammer for striking the pattern-support and vibrating it horizontally, a pattern movable up and down relatively to the pattern-support, and a pressure-actuated hammer for vibrating the pattern up and down in the flask independently of the horizontal vibration of the pattern-support. 55

6. In a sand-molding machine, the combination with a support for the flask, of a tamping-frame carrying a series of independent tampers, columns at the sides of the frame, cylinders surrounding said columns and attached to said frame, pistons on said columns inside 60 said cylinders, and means for controlling a supply of fluid-pressure to said cylinders. 70

In testimony whereof we have signed our names to this specification in the presence of two subscribing witnesses.
